Des. 202,617
Patented Oct. 26, 1965

202,617

CAMPER

David G. Foss, 2027 W. Gramercy, San Antonio, Tex.

Filed Jan. 6, 1965, Ser. No. 83,284

Term of patent 14 years

(Cl. D14—3)

FIGURE 1 is a perspective view of a camper showing the top, front and one side of my new design; with the truck shown in broken lines being included for illustrative purposes only; and

I claim:

The ornamental design for a camper, substantially as shown and described.
